Primary Examiner — Kevin K Rudzinski
Assistant Examiner — Clare Ann Gannon(57) **CLAIM**

The ornamental design for a frame cellular shade, as shown and described.

DESCRIPTION

FIG. 1 is a top and front side perspective view of a frame cellular shade, showing my new design;

FIG. 2 is a front view thereof;

FIG. 3 is a back view thereof;

FIG. 4 is a right view thereof;

FIG. 5 is a left view thereof;

FIG. 6 is a top view thereof; and,

FIG. 7 is a bottom view thereof.

The broken lines in the drawing depict environmental subject matter only and form no part of the claimed design.
